DISPLAY DEVICE

George Stephen Snyder, New York, N. Y., assignor
to Salers, Inc., New York, N. Y., a corporation of
New York

Application February 23, 1950, Serial No. 8,088

Term of patent 14 years

(Cl. D80—1)

To all whom it may concern:

Be it known that I, George S. Snyder, a citizen of the United States of America, residing at New York, county of New York, and State of New York, have invented a new, original, and ornamental Design for a Display Device, of which the following is a specification, reference being had to the accompanying drawing, forming part thereof.

Fig. 1 is an isometric view of a display device, showing my new design.

Fig. 2 is a fragmentary sectional view taken on the plane of the line 2—2 of Fig. 1.

Fig. 3 is a fragmentary sectional view taken on the plane of the line 3—3 of Fig. 1.

The appearance of the right-hand side of the display device not shown is the same as the left-hand side, and the appearance of the rear side

not shown is the same as the front side. The appearance of the bottom end not shown is the same as the top end.

I claim:

The ornamental design for a display device, substantially as shown and described.

GEORGE STEPHEN SNYDER.
